vention, are given by way of illustration only, since various changes and modifications within the spirit and scope of the invention will become apparent to those skilled in the art from this detailed description.

Summary of the invention

According to the present invention, it has been found that a more effective apparatus for the heat-treatment of textile materials can be obtained by locating the fan drives outside of the treatment housing. According to the present invention, the fan shaft is supported on two separate pillow blocks or block bearings outside of the dryer housing thus permitting easy accessibility for servicing the bearings while the apparatus is being operated. Furthermore, it is no longer necessary to let the apparatus cool down before replacing one or both bearings. In performing maintenance work on presently used sieve drums which operate at treatment temperatures of about 200° C. and higher, it is necessary to provide for a cooling down period of at least about one hour. According to the present invention, the bearings can now be replaced in a minimum of time, generally less than about ten minutes due to the lower environmental temperatures they are exposed to as well as the ready accessibility of the bearings themselves.

According to another embodiment of the present invention, the fan bearings and the bearings of the fan motor can be combined into a single unit by mounting said bearings to a drive box which also supports the fan motor. For example, the fan motor may be disposed beneath the fan bearing so that no additional space is required except that normally used by the fan motor. In order to prevent the bearings from overheating due to the heat of conduction by the fan shaft, the apparatus of the present invention also provides for a disc containing cooling coils which is mounted to the shaft outside of the housing. This disc provides a means for cooling the fan shaft and the bearings and additionally and simultaneously produces a current of air which flows around the fan motor thus cooling it. In general, the fan motor and the fan shaft are connected by V-belts. For tensioning and retensioning the V-belts, the motor which is attached to the drive box is adjustably supported to the fan shaft. Thus, by operating an adjustable screw located on the outside of a casing means which encloses the fan drives, the fan motor can be adjustably moved toward or away from the fan shaft. As just stated, it is advantageous to provide all fan driving units outside of the treatment housing with a protective casing which is preferably perforated. Such a casing does not only offer protection to the operators but also improves the overall appearance of the apparatus.

In order to facilitate maintenance, especially the replacement of the bearings, it is also desirable to provide in the fan chamber and/or outside the fan chamber adjustable supporting means for supporting the fan wheel and/or the fan shaft in the case of assembly work. Accordingly, two tubes or rails which are vertically adjustable beneath the fan wheel are arranged for supporting the fan wheel. It is also desirable if the adjusting means for the supporting elements can be operated from outside of the treatment housing or if a door is provided in the housing near the adjusting device to provide for easy accessibility and operation thereof. If the adjusting means is operated from outside the treatment housing, a reversible ratchet with a lever arm extending through a sealed aperture in the frame supporting the rails can be provided as shown in FIGURE 6. However, it is advantageous if the actuating elements and/or at least one actuating element of the adjusting means, for example, the set screws or the handwheel, is disposed outside of the hous-

ABSTRACT OF THE DISCLOSURE

The present disclosure relates to an apparatus for the heat-treatment of textile materials, such as for example, 15 drying, steaming, fiber and dyestuff setting, curing and polymerizing synthetic resins, etc., wherein the fan drives are arranged outside the heat-treatment housing and the fan shaft is not supported in the housing of the apparatus but rather outside said housing by bearing means.

The present invention relates to an apparatus for the heat-treatment of textile materials, such as for example, 20 drying, steaming, fiber and dyestuff setting, curing and polymerizing synthetic materials, etc. However, the apparatus of the present invention is also suitable for drying veneers, cardboard webs and other materials, as well as 25 cooling and conditioning materials, as well as carbonizing of wool and neutralizing after a treatment with acids or alkalis. More particularly, the present invention concerns an apparatus for the heat-treatment of textile materials which comprises a housing, at least one cylindrical sieve drum rotatably disposed within said housing, fan means correlated to the faces of sieve drum, the fan drives for said fan means being arranged outside the 30 treatment housing.

Apparatus comprising sieve drums subjected to a suction draft are well known wherein fan wheels are coaxially correlated to the faces of the sieve drums for exhausting the treatment medium out of the sieve drums. Since these fan wheels operate at very high speeds, the fan shaft, in known devices, is supported in close proximity to the fan wheel, that is, the fan shaft is supported in the housing of the heat-treatment apparatus. This disposition of the fan shaft supporting means is disadvantageous in that the fan bearings are exposed to elevated treatment 35 temperatures necessitating extended stoppages to permit the apparatus to cool down before repair work can be commenced. Thus, for example, when it is necessary to replace a bearing, the heat-treatment process must be stopped and the apparatus must be allowed to cool down before repair work on the apparatus can begin.

Accordingly, it is an object of the present invention to avoid these prior art disadvantages in heat-treatment apparatus.

Another object of the present invention is to improve the economy of heat-treatment apparatus by eliminating the cooling down period necessary when performing maintenance and repair work on the fan drives.

A further object of the present invention is to provide an improved apparatus for the heat-treatment of textile materials wherein the fan drives and the associated bearing means and adjusting devices therefor are disposed outside of the treatment chamber.

Other objects and further scope of applicability of the present invention will become apparent from the detailed description given hereinafter; it should be understood, however, that the detailed description and specific examples, while indicating preferred embodiments of the in-

ing so that the apparatus need not be opened for supporting the fan wheel.

In another embodiment of the present invention, the fan shaft can be supported to facilitate the replacing of the bearings. For this purpose, a bearing block which is advantageously adjustable in the vertical direction is provided in the housing, and outside the housing a clamping device which can be composed of two adjustable parts is disposed at the fan shaft. After mounting the fan wheel, the bearing block may be adjusted so that it is situated beneath the fan shaft and provided with a small amount of play relative thereto so that in case of repair work the bearing block need not be lifted. The two components of the clamping device provided outside of the treatment housing are adjustably connected to each other by screw means and are extended from each other and from the fan shaft by means of spiral springs circumferentially disposed around said screw means. By tightening the screw means the two components of the clamping device are moved toward each other and the fan shaft is fixed thereby.

Whereas the outer bearing of the fan shaft can be easily removed after removing the V-belt, it is often advantageous to design the bearing of the fan shaft at the housing as a two-part pillow block and to support the lower bearing part in such a manner that it can be readily lowered. For example, the base supporting the bearing can be further supported by a bracket which is adjustably attached to the housing wall.

Brief description of the drawings

The present invention will become fully understood from the detailed description hereinbelow and the accompanying drawings which are given by way of illustration only and thus are not limitative of the present invention and wherein,

FIGURE 1 is a cross-sectional view of a sieve drum dryer according to the present invention;

FIGURE 2 is a section of the fan wheel bearing of the present invention;

FIGURE 3 is a plan view of the supporting means of the fan wheel according to FIGURE 2;

FIGURE 4 is a profile view of the fan wheel with supporting means with the insulation of the housing removed;

FIGURE 5 is a section view of another fan wheel bearing according to the present invention;

FIGURE 6 is a section view along line 6—6 of the embodiment according to FIGURE 5.

FIGURE 7 is a detailed view illustrating how the lower shell of the bearing can be lowered.

Description of the preferred embodiments

Referring now to the drawings wherein like reference numerals are used throughout the various views to designate like parts, the apparatus of the present invention comprises a housing 1 which is subdivided by a partition 2 into a treatment chamber 3 with sieve drums 4 subjected to a suction draft, and a fan chamber 5 with a fan wheel 6 correlated to the face of each sieve drum. Heaters 7 are arranged above and beneath the fan wheel. At one longitudinal side of the sieve drum, drives 8 are provided for the sieve drums 4, and at the other longitudinal side a drive 9 for the fan wheels 6 is provided. These sieve drums can be arranged in one row or in two rows staggered to each other.

According to the embodiments of the present invention, the fan wheel is supported unilaterally on a fan shaft 10. The fan shaft 10 is supported by means of two separate pillow blocks (bearings) 11 and 12 which, in FIGURE 2, are mounted to a drive box 13. Furthermore, a fan motor 14 is adjustably supported to the fan shaft 10 on the drive box 13 by set screw 13a. By using this adjustable support for the fan motor 14, a simple tensioning and retensioning

of V-belts 15 is ensured. For cooling the fan shaft 10 and the bearings 11 and 12, a disc 16 with cooling coils is disposed on the fan shaft just outside of the treatment housing. All of the driving parts are covered by a perforated casing 17 which is set up on the drive box 13 and in some cases attached or screwed thereto.

For supporting the fan wheel 6, especially when replacing bearings 11 and 12, rails 18 are provided beneath the fan wheel, said rails being slidably supported and adjustable in height in frame 19. A handwheel 20 serves for adjusting the height of each rail 18. The two handwheels 20 may be operated from the outside through a door 21 provided in the treatment housing. The door can also be offset toward the inside and affixed to the frame 19 as shown in FIGURE 2 to provide ready access to handwheel 20. This modification is shown as 21a in FIGURE 2. For better heat insulation, a sheet 22 is mounted to frame 19.

In the apparatus of the present invention according to FIGURES 5 and 6, supporting elements are provided for supporting the fan shaft 10. In the case of this embodiment a bearing block 24 which can be adjusted in the vertical direction by means of screws 23 is disposed just beneath the fan shaft 10 in the fan chamber 5. The bearing block 24 can also be raised and lowered in the vertical direction together with the supporting beams carrying the same. The screw bolt 34 is rotatable with respect to the cross bearer member 35 (transverse girder) of the frame 19 but is positioned so as to be axially non-displaceable with respect thereto. However, the screw bolt is axially displaced during a rotation with respect to the supporting beam 36 under the bearing block 24, thus effecting the raising and lowering of the supporting beam whose thread is in engagement with the thread of the screw bolt. When adjusting the bearing block from the outside, a reversible ratchet 32 with a lever arm 31 extending through a sealed aperture 33 in the frame supporting the rails can be provided as shown. The opening in the frame wall 19 is so large that the lever 31 is adapted to execute any kind of pivoting movements. A rubber sleeve 37 seals the opening. Outside the housing, a two-component clamping device 25a and 25b is provided between disc 16 and bearing 11. The upper bridge-shaped part 25a is connected with the lower part 25b by means of two screws 26. Screw springs 27 are slipped around the screws, said springs supporting the upper part 25a of the clamping device so that it does not come into contact with the fan shaft 10. However, if the screws 26 are tightened, the upper component 25a of the clamping device is forced against the fan shaft 10 and the shaft is accordingly fixed. In this embodiment of the present invention the lower portion of the bearing 11 is supported on a base 28 which is further supported on a bracket 29 which is adjustably attached to the housing wall by set-screw 30, so that it can be lowered for ready replacement of the bearing ring (see FIGURE 7).

Since modifications of the present invention will be apparent to those skilled in the art, it is not desired to limit the invention to the exact constitution shown and described. Accordingly, all suitable modifications and equivalents may be resorted to which fall within the scope of the appended claims.

We claim:

1. An apparatus for the treatment of textile materials which comprises a housing, at least one cylindrical sieve drum rotatably disposed within said housing, fan wheel means correlated to the faces of said sieve drum, said fan wheel means containing a fan shaft supported outside of said housing and a fan drive disposed outside of said housing, said fan wheel means being supported by adjustable supporting means during assembly.

2. The apparatus of claim 1, wherein the fan shaft is supported by two bearing blocks.

3. The apparatus of claim 2, wherein the bearing blocks and a fan motor are supported by a drive box.

4. The apparatus of claim 2, wherein the bearing blocks are divided into two portions and are supported by a vertically adjustable bracket means which is attached to the housing wall, thereby providing for lowering the lower portion of the bearing blocks.

5. The apparatus of claim 3, wherein the fan motor which is attached to the drive box is adjustably disposed relative to the fan shaft.

6. The apparatus of claim 1, wherein a disc means provided with cooling coils is attached to the fan shaft outside of the treatment housing for cooling the bearing and the fan shaft.

7. The apparatus of claim 1, wherein all of the fan driving units disposed outside of the treatment housing are enclosed in a casing means.

8. The apparatus of claim 1, wherein during assembly work the fan shaft is supported by adjustable supporting means.

9. The apparatus of claim 1, wherein a height-adjustable bearing block located inside of the housing and a clamping means disposed outside of the housing are provided for supporting the fan shaft.

10. The apparatus of claim 9, wherein said clamping means comprises an upper and a lower portion connected by spring-extended screw means.

11. The apparatus of claim 1, wherein the adjustable supporting means are rail means which are adjustable in the vertical direction and disposed beneath the fan wheel means for supporting said fan wheel means.

12. The apparatus of claim 11, wherein the adjusting means for the supporting means are located outside of the treatment housing.

13. The apparatus of claim 12, wherein at least one actuating element of the adjusting means is disposed outside of the treatment housing.

14. The apparatus of claim 11, wherein a door is positioned in the housing adjacent the adjusting means for an easier operation of said adjusting means.

15. The apparatus of claim 13, wherein the adjusting means is a handwheel.

16. The apparatus of claim 13, wherein the adjusting means is a set screw.

17. An apparatus for the treatment of textile materials which comprises a substantially closed housing, at least one sieve drum means rotatably disposed within said housing, fan wheel means disposed at one end of the sieve drum means, said fan wheel means containing a fan shaft

which is coaxially disposed with respect to the sieve drum means and extends through the wall of the housing, means for supporting the fan shaft on the outside of the housing, fan drive means disposed outside of the housing and communicating with said fan shaft, and adjustable supporting means for supporting the fan wheel means during assembly, said adjustable supporting means comprising rail means which are vertically adjustable and disposed beneath the fan wheel means in the housing for supporting said fan wheel means.

18. The apparatus of claim 17, wherein the rail means are supported by a frame which is attached to the inside of the housing wall.

19. The apparatus of claim 18, wherein means are provided inside the housing near the housing wall for raising or lowering the adjustable supporting means.

20. The apparatus of claim 19, wherein the housing wall is provided within a door near the adjustable supporting means for ready accessibility to the supporting means.

21. The apparatus of claim 20, wherein the door means is offset toward the inside of the housing and affixed to the frame, thereby providing ready access to the means for raising or lowering the adjustable supporting means.

22. The apparatus of claim 17, wherein the fan shaft is supported outside of the housing by bearing blocks.

23. The apparatus of claim 22, wherein the bearing blocks are divided into two portions and are supported by a vertically adjustable bracket means which is attached to the housing wall, thereby providing for lowering the lower portion of the bearing blocks.
